UNITED STATES PATENT OFFICE.

FRED A. NEIDER, OF AUGUSTA, KENTUCKY.

TUFTING-FRAME.

SPECIFICATION forming part of Letters Patent No. 686,633, dated November 12, 1901.

Application filed July 5, 1901. Serial No. 67,078. (No model.)

To all whom it may concern:

Be it known that I, FRED A. NEIDER, a citizen of the United States of America, and a resident of Augusta, in the county of Bracken 5 and State of Kentucky, have invented certain new and useful Improvements in Tufting-Frames, of which the following is a specification.

The object of my invention is a frame to be 10 used in forming tufted cushions by hand in place of the tufting-boards now in use.

In tufting-boards there are a series of perforations through which the prongs of the tufting-buttons project after having passed 15 through the cover and the burlap to enable the workman to place a washer over them next to the burlap and bend the prongs down to hold the tufts in place. Manipulating the washer and the prongs within these perforations is an awkward proceeding, the result of 20 which is attained in a much simpler and quicker manner with the frame embodying my invention, of which—

Figure 1 is a perspective view showing the 25 extensible ends contracted. Fig. 2 is a similar view of the same, but with the ends extended for use in forming a wider cushion than that formed upon the frame as shown in Fig. 1. Fig. 3 is a vertical transverse section 30 taken upon line z z, Fig. 2.

Referring to the parts, frame A consists of front and rear vertical longitudinal members a and a', connected by vertical transverse end members, each of which consists of two 35 sections a² and a³, respectively, the former having a central vertical slot a⁴ in its end, into which a tongue a⁵ upon the latter fits. Section a² has near its end a series of vertically-aligned perforations a⁶ crossing slot a⁴. 40 Tongue a⁵ has two series of such perforations. When the end members are extended, the set 45 of said perforations nearer the end of the tongue register with perforations a⁶, and pins are passed through them to hold the end members extended. When the end members are contracted, the inner set of perforations in tongue a⁵ register with perforations a⁶ to receive the pins.

A series of longitudinal wires B cross the 50 frame at a short distance apart, a distance of about four inches being found to be right, and are secured to the end members thereof. To

allow of the extension of the tufting-frame, one of these wires B' is secured to tongues a⁵ and another wire B² to members a² across slot a⁴, so that when the end members are contracted, as shown in Fig. 1, wires B' and B² stand closely side by side and when said sides are extended stand the same distance apart as the rest of the wires, the two series of perforations in tongue a⁵ being spaced at that distance apart.

Front member a has a longitudinal opening a⁷. In use backing or burlap C is stretched over wires B and is tacked to the sides of the 65 frame, being tacked in front below opening a⁷. Cover D has the points through which the tufting-buttons E are to pass marked upon it before it is laid upon the burlap. After the cover has been placed upon the burlap 70 one row of tufting-buttons are passed through the cover and burlap and bent down upon the burlap, or, if washers are used, upon the washers. The separate biscuits are then filled by hand with the filling F, as customary, and 75 the prongs of the buttons passed down through the cover and the burlap to complete the biscuits. It is seen that the workman in placing the washers over the prongs and in bending the prongs down has a free access to the 80 parts and is not hampered by having to work in a limited space, like the perforations in tufting-boards.

In forming the front tufts of the cushion-opening a⁷ makes it easy for the workman to 85 clench the prongs of the row of tufting-buttons below the rounded edge of the cushion. After the cushion has been completed it is taken from the frame by removing the tacks securing the burlap to the frame. 90

What I claim is—

1. For use in forming tufted cushions, a frame having a series of wires extending across its top and secured to its sides over which the backing is secured in the process 95 of forming the cushion, substantially as shown and described.

2. A frame consisting of rear and front members connected by extensible side members in combination with wires crossing the frame 100 and secured to said side members over which the backing is to be secured in forming tufted cushions, substantially as shown and described.

3. For use in forming tufted cushions a frame consisting of front and rear members connected by side members the front member having a longitudinal opening extending across it said frame having a series of wires extending across its top and secured to its sides over which the backing is secured in

the process of forming a cushion, substantially as shown and described.

FRED A. NEIDER.
